WAVE GENERATING SYSTEM

Carl G. Sontheimer, Riverside, Conn., assignor to
 Radio Corporation of America, a corporation of
 Delaware

Application May 30, 1945, Serial No. 596,685

5 Claims. (Cl. 320—1)

1

The present invention relates to wave generating systems, and more particularly to a system for generating sawtooth waves having substantially linear leading edges.

The invention is concerned primarily with the generation of cyclically varying potentials wherein each cycle comprises a relatively slow potential variation in one direction followed by a relatively rapid potential variation in the opposite direction.

Voltages of the above nature may be employed, for instance, for the time-base deflection of the electron beam developed in cathode ray tubes used for television and oscillographic purposes. In television receivers, for example, reconstitution of a line of the transmitted image occurs during the slow motion of the cathode ray beam, while the rapid motion comprises the return stroke (during which the cathode ray beam is usually suppressed) which is necessary before the next following line of the image can be reconstituted. One of the requirements of such arrangements is that the slow motion of the beam shall be a uniform one, as otherwise distortion of the reproduced image results.

The complexity of conventional circuits for generating sawtooth waves increases in approximate proportion to the linearity of their output. The simplest system in general use is that in which a condenser is charged through a resistance from a source of potential and then discharged through a second lower resistance, (usually a tube) the process being repeated for each cycle of the wave. This latter system, however, yields an output voltage which rises exponentially with time.

According to a feature of the present invention, the linearity of output from a single condenser network such as above described is materially improved by the addition of a second condenser having a separate charging path connected to the same potential source. The two condensers are then charged simultaneously, the output of the added condenser being applied during the charging interval to the original condenser to act in effect as an increase in source potential during the initial portion of the charging interval. As a result, the circuit output voltage has a substantially more linear characteristic than the output of the single condenser network alone.

One object of the present invention, therefore, is to provide a simple and effective system for generating sawtooth waves the leading edges of which are substantially linear.

A further object of the present invention is to provide two energy-storage networks adapted to

2

be simultaneously charged, the output of one of said networks being applied to the other of said networks during the charging interval to cause the charge on the latter to increase substantially proportionally with respect to time during a greater portion of the charging interval than would normally be the case as a result of the charging of the latter network alone.

Other objects and advantages will be apparent from the following description of a preferred form of the invention and from the drawings, in which:

Fig. 1 is a circuit diagram of a preferred form of the present invention;

Fig. 2 is a graph useful in explaining the operation of the circuit of Fig. 1; and

Fig. 3 is a circuit diagram illustrating an alternative arrangement in accordance with the invention.

Referring first to Fig. 1, there is shown a sawtooth wave generating circuit including three switches S_1 , S_2 , and S_3 , each of which will be assumed to be open for the purposes of the following description setting forth mainly the principles of operation. A triode V_1 , normally biased to cut-off by any suitable means such as a source of negative potential, (not shown), is rendered conductive when periodically recurring substantially rectangular pulses P of positive polarity are received on the control electrode thereof. During the time that triode V_1 is non-conductive, a condenser C_1 in parallel with triode V_1 is charged through a resistor R_1 from a source of positive potential B . As is well known, the charge E_{c1} on condenser C_1 will rise exponentially with time t , as shown in Fig. 2, and will depart from a condition of linearity, which has been represented by the broken line L . When triode V_1 is rendered conductive by the reception of a positive pulse P of duration t_1 on the control electrode thereof, condenser C_1 discharges through the tube, the plate resistance of which has a value chosen to be much smaller than the value of resistor R_1 .

The sawtooth wave thus produced by that portion of the circuit of Fig. 1 including elements V_1 , R_1 , and C_1 has an exponential voltage rise given by the equation

$$E_{c1} = E_b \left(\frac{1 - e^{-t}}{RC_1} \right) \quad (1)$$

50 where

E_{c1} =charge on condenser C_1

E_b =voltage of battery B

e =base of the natural system of

55 logarithms=2.718

The above equation can also be expressed as follows

$$\frac{E_{C_1}}{E_B} = \frac{t}{RC_1} - \frac{1}{2!} \left(\frac{t}{RC_1} \right)^2 + \frac{1}{3!} \left(\frac{t}{RC_1} \right)^3 \dots \quad (2)$$

It will be clear from the above equations that the voltage rise on condenser C_1 will be substantially linear only if the expression

$$\frac{E_{C_1}}{E_B}$$

is maintained small, or in other words if C_1 is charged only to a small fraction of the battery voltage E_B . For example, if E_{C_1} is allowed to rise to 10% of E_B , then from the above equations it can be shown that the non-linearity due to the quadratic term will be in the order of 5%.

The non-linearity inherent in the operation of a circuit of the above nature is materially reduced by means of the present invention. In the left-hand portion of Fig. 1 is shown a second wave generating network substantially identical to the network shown in the right-hand portion of Fig. 1. This second network includes a triode V_2 , a parallel condenser C_2 , and a charging resistor R_2 . The grid of triode V_2 is biased to cut-off in the same manner as is the grid of triode V_1 . When switch S_2 is closed, the plate of triode V_2 is connected to the plate of triode V_1 through an additional resistor R_3 , while the battery end of resistor R_2 is connected to the battery end of resistor R_1 through switch S_1 , as shown. The positive pulses P applied to triode V_1 are also applied upon closing of switch S_3 to triode V_2 so that both tubes are triggered simultaneously.

A consideration of the circuit of Fig. 1 will show that capacity C_1 charges exponentially through R_1 during the interval t_2 during which triode V_1 is cut off, if switches S_1 , S_2 and S_3 are open. Assume now, however, that switches S_1 , S_2 and S_3 are closed. If resistor R_1 were removed, capacity C_1 would charge through resistors R_2 and R_3 . However, since the voltage on capacity C_2 is zero at the beginning of charging interval t_2 (triodes V_1 and V_2 are triggered together), it is apparent that the current through capacity C_2 is zero at the beginning of charging interval t_2 , and therefore the equation for the charge on capacity C_1 can have no linear time term. It will instead be of the form

$$\frac{E_{C_1}}{E_B} = a_2 t^2 + a_3 t^3 + \dots \quad (3)$$

where a_2 and a_3 are constants.

The constants of the circuit of Fig. 1 may be chosen so that the non-linearity introduced by the charging path through resistors R_2 , R_3 bucks out in part the non-linear terms in the exponential series representing the charge through resistor R_1 . For example, the quadratic term in the equation for the charge on capacity C_1 may always be made to vanish if the circuit constants are so chosen that

$$\frac{R_1 C_1}{R_2 C_2} = 1 + \frac{R_3}{R_1} \quad (4)$$

This may be accomplished for example by setting

$$R_1 = R_2 = R_3 \quad (5)$$

and

$$C_1 = 2C_2 \quad (6)$$

The following table illustrates the improvement in linearity of output voltage from the two-condenser network in the circuit of Fig. 1 as compared with the linearity of charge obtained

on the single condenser network alone. The relative output of the two networks is likewise shown graphically by the curves in Fig. 2. These curves have not been drawn to scale, however, and are merely intended to illustrate the relationship of the voltage output of the two networks.

10	(single-condenser network with switches S_1 , S_2 and S_3 open)		(two-condenser network with switches S_1 , S_2 and S_3 closed)	
	$\frac{t}{RC_1}$	$\frac{E_{C_1}}{E_B}$	$\frac{E_{C_1}}{E_B}$	$\frac{E_{C_1}}{E_B}$
15	.001 (.1%)	.0000000	.001000	
	.01 (1%)	.009995	.01002	
	.1 (10%)	.035	.038	

From the above table it will be seen that the departure from linearity of the two-condenser network, with switches S_1 , S_2 and S_3 closed and allowing C_1 to charge up to 10% of E_B , is approximately 1.2%; whereas for the single-condenser network with switches S_1 , S_2 and S_3 open, the departure is approximately 5% for the same values of circuit components. Expressed in other terms, the single-condenser network requires about four times as much battery voltage (E_B) to limit the distortion to 1.2% for the same maximum output voltage as the two-condenser network of the present invention.

The condenser C_2 of Fig. 1 may be charged through resistor R_2 from a separate source of potential B_1 as shown in Fig. 3, instead of from the common sources B as in the former figure. By varying the relative voltages of sources B and B_1 , differently compensated charging curves may be obtained.

While I have shown and described, and have pointed out in the annexed claims, certain novel features of my invention, it will be understood that various substitutions, omissions and changes in the form and details of the system illustrated may be made by those skilled in the art without departing from the spirit of the invention. For example, while only two charging networks have been shown, it will be understood that such showing may be extended to include further charging networks added to the system in the manner hereinabove described, each additional charging path resulting in a higher order of linearity. Similarly, it will be appreciated that tubes of other types than triodes may be used as the discharge elements.

55 I claim:

1. A wave-generating system comprising a first condenser, means for periodically charging and discharging said first condenser, a second condenser, means for periodically charging and discharging said second condenser respectively concurrently with the operation of the first-mentioned charging and discharging means, and means for applying the charge on said second condenser to said first condenser to thereby lengthen that portion of each charging period during which the charge on said first condenser increases substantially linearly with time as a result of the operation of said first-mentioned charging means alone.

70. 2. A wave-generating system comprising a first energy-storage means, means for periodically charging and discharging said first energy-storage means, a second energy-storage means, means for periodically charging and discharging said second energy-storage means respectively con-

currently with the operation of the first-mentioned charging and discharging means, and means for applying the charge on said second energy-storage means to said first energy-storage means to thereby lengthen that portion of each charging period during which the charge on said first energy-storage means increases substantially linearly with time as a result of the operation of said first-mentioned charging means alone.

3. In a device of the class described: a first condenser; a first resistor; a source of potential; means for charging said first condenser through said first resistor from said source of potential; a second condenser; a second resistor; means for charging said second condenser through said second resistor from said source of potential concurrently with the operation of said first-mentioned charging means; a third resistor; and means for applying the charge on said second condenser to said first condenser through said third resistor.

4. A device in accordance with claim 3, further comprising means for simultaneously discharging both said condensers.

5. A device in accordance with claim 3, further comprising two electron discharge devices respectively connected in parallel with said condensers, said electron discharge devices being normally non-conductive, and means for rendering both said electron discharge devices conductive simultaneously to respectively discharge said condensers therethrough.
